UNITED STATES PATENT OFFICE.

FRANK M. GAULT, OF OKLAHOMA, OKLAHOMA TERRITORY.

POULTRY-SHIPPING COOP.

No. 809,558.

Specification of Letters Patent.

Patented Jan. 9, 1906.

Application filed September 3, 1904. Serial No. 223,265.

To all whom it may concern:

Be it known that I, FRANK M. GAULT, a citizen of the United States, residing at Oklahoma, in the county of Oklahoma and Territory of Oklahoma, have invented new and useful Improvements in Poultry-Shipping Coops, of which the following is a specification.

My invention relates to improvements in poultry-shipping coops consisting of a floor secured to sills having wires inserted therein at suitable intervals and standing vertical to the base, and at a suitable distance from the floor said wires assume a horizontal position, forming a roof, double strength, the upright wires having horizontal ribs or stays and all crossings of wires firmly held in position by clamps, the roof having a door centrally located therein; and the objects of my invention are, first, to provide a strong coop for shipping or transporting poultry; second, great durability; third, convenience; fourth, security from escape of the contents; fifth, adaptability of form. I attain these objects by the mechanism illustrated in the accompanying drawings, in which—

Figure 1 is a view in perspective of the entire coop with the door removed. Fig. 2 is a transverse sectional view on the line *y x* in Fig. 1. Fig. 3 is a plan view of the door. Fig. 4 is a side view of one of the cross-bars of the door. Fig. 5 is a view in perspective of the door-fastening device.

Similar letters refer to similar parts in the several views.

The floor *c* is firmly secured to sills *a a a a* and *a'*. Wires or rods *e* have a portion of their lower ends bent at right angles, forming feet, which at regular intervals are inserted into or through the four sills *a* and rising vertically to a convenient distance from the floor, then assuming a horizontal position, forming a roof. Horizontal rods or wires, firmly se-

cured to the vertical wires *e*, form ribs or stays *f*, all lateral intersections of wires or rods being firmly attached.

The roof *G* of the coop *A* is provided with a door *B* for the insertion and removal of poultry. The gate or door proper, *D*, is constructed of U-shaped rods *j* of varying sizes, the outer one being the larger and they being secured to cross-bars *i*, having their ends bent into a circle forming rings or eyes *i'*, said eyes being adapted to encircle and slide upon the door-supporting rods *d*, the elbow ends *d'* of which are attached to the roof *G* of the coop. The door latch or hook *E* is secured to the under surface of the roof, the eyes *m m* encircling one of the rods or wires forming the roof. The ends *n*, pressing against the roof, hold the end *o* in close proximity to the roof, but permit the rod *j* to slide over the hook *o'*, and thus prevent any accidental opening of the door.

I do not claim the device *b* for clamping the wires or rods as my invention. I use this style of clamp as being preferable for this purpose; but

What I do claim, and desire to secure by Letters Patent, is—

As an article of manufacture, a rectangular, inclosed shipping-coop *A*, comprising a floor *c*, sills *a* and *a'*, supporting the floor, vertical rods *e* inserted into the sills *a* and *a'*, by right-angled projections, for side and end walls, and bent at their upper ends to form a roof *G*, having a central opening *B*, a door *D*, provided with a fastening device *E*, substantially as described.

In testimony whereof I have signed my name to this specification in the presence of two subscribing witnesses.

FRANK M. GAULT.
